FIG. 1

FIG. 2

FIG. 3

FIG. 4

FIG. 5

FIG. 1 is a side view of a combined hand-held warning sign and blinking light and battery case therefor showing my new design;

FIG. 2 is an end view thereof as taken from the right of FIG. 1;

FIGS. 3 and 4 are respectively, bottom and top views thereof, the battery case being omitted for convenience of illustration; and

FIG. 5 is a view of the side opposite that shown in FIG. 1.

The electric cord is broken away in FIGS. 1, 2 and 5 to indicate indeterminate length. The cross-hatching on the battery case is partially shown for convenience of illustration, it being understood that the cross-hatching is uniformly continuous over the surfaces indicated. The

indicia is shown in broken lines in FIGS. 1 and 5 for illustrative purposes only.

I claim:

The ornamental design for a combined hand-held warning sign and blinking light and battery case therefor, as shown and described.
